US00D800121S

(12) **United States Design Patent** (10) **Patent No.:** **US D800,121 S**
(45) **Date of Patent:** **** Oct. 17, 2017**

(54) **OPTICAL SCANNING DEVICE**

(71) Applicant: **Akers BioSciences, Inc.**, Thorofare, NJ (US)

(72) Inventors: **Raymond F. Akers, Jr.**, Sewell, NJ (US); **Richard E. McKee**, Pilesgrove, NJ (US); **Michael Alan Feldman**, Pottstown, PA (US)

(73) Assignee: **Akers Biosciences, Inc.**, Thorofare, NJ (US)

(**) Term: **15 Years**

(21) Appl. No.: **29/564,404**

(22) Filed: **May 12, 2016**

(57) **CLAIM**

The ornamental design for an optical scanning device, as shown and described.

DESCRIPTION

FIG. 1 is a front and left side perspective view of an optical scanning device in accordance with our new design;

FIG. 2 is a front elevational view thereof;

FIG. 3 is a rear elevational view thereof;

FIG. 4 is a left side elevational view thereof; a right side elevational view being a mirror image thereof;

FIG. 5 is a top plan view thereof; and,

FIG. 6 is a bottom plan view thereof.

The broken lines in the figures are directed to environment and are for illustrative purposes only; the broken lines form no part of the claimed design.
